UNITED STATES PATENT OFFICE.

EDWARD H. CALLAWAY, OF NEW YORK, N. Y., ASSIGNOR OF ONE-HALF TO
GEO. W. SHARER, OF PHILADELPHIA, PENNSYLVANIA.

SAND AND GRAVEL HEATER.

SPECIFICATION forming part of Letters Patent No. 448,408, dated March 17, 1891.

Application filed September 9, 1889. Serial No. 323,347. (No model.)

To all whom it may concern:

Be it known that I, EDWARD H. CALLAWAY, a citizen of the United States, residing at New York, in the county of New York and State 5 of New York, have invented certain new and useful Improvements in Sand and Gravel Heaters; and I do hereby declare the following to be a full, clear, and exact description of the invention, such as will enable others 10 skilled in the art to which it appertains to make and use the same.

My invention relates to driers generally, and sand and gravel driers particularly.

The object of my invention is to provide a 15 simple and efficient machine for drying sand and gravel in a quick and thorough manner without requiring any manipulation of the sand or gravel while in the drier.

As is well known, wet sand or gravel is more 20 or less cloggy, and in all the driers that I am aware of the sand or gravel must be kept moving by stirring or other motion by hand or by machinery, so that the person feeding the drier must devote more or less time to this 25 object if done by hand, and if operated by machinery expensive power must be used to reach the desired result. In my device these 30 objections are overcome by the particular arrangement of pipes, which are so placed that the sand or gravel is kept moving by its own gravity and is broken or unclogged by falling upon the pipes below, which are hotter than those above.

The invention consists of constructions and 35 combinations, all as will hereinafter be described in the specification, and pointed out in the claims, reference being had to the accompanying drawings, in which—

Figure 1 represents a longitudinal section; 40 Fig. 2, a transverse partial section on line 1 1/2 of Fig. 1, the ends of the flues being in full lines; and Fig. 3, a longitudinal section of a modified form.

A represents a furnace of any suitable construction and having a fuel-supplying opening A⁶ and a main flue A', leading to a vertical flue or chamber A², located at the opposite end of the machine. This vertical flue or chamber is constructed of any desired material, and, as shown, is made of brick and

closed at the top and provided with an opening A⁷ for the removal of soot. In the front wall a are secured flues a', which extend to a second vertical flue or chamber A³, located in the rear of furnace A and connected at its 55 upper end to a chimney A⁴ of any suitable construction. The flues a' are inclosed on the sides by the side walls A⁵, which may be of wood or sheet metal. When made of wood, the lower end of each side wall is provided 60 with metal sheet a², which projects below the lower edge of the side walls to protect the lower ends thereof from the heat of the main flue A'. These side walls are inclined from the upper edges inward and downward toward 65 the main flue A', so that all the sand will strike said flue before passing out of the drier. The side walls are preferably supported by bars A⁶, to which they are secured in any suitable manner. The flues a' are arranged in 70 rows gradually decreasing in number, and in cross-section present substantially a wedge-shaped form, the flue A' being the apex. The areas of these flues combined are equal to the area of flue A', so that the products of combustion will be equally distributed in passing 75 from flue A' to the smaller flues.

The vertical flue or chamber A³, as before stated, is located immediately behind the furnace. It is also immediately above the front 80 end of flue A', from which it is separated by a thin partition, so that the products of combustion passing into the vertical flue or chamber A³ will be more or less heated to increase the draft through the flues. By making the flue 85 A' inclined, as shown in Fig. 1, better results are obtained, as the products of combustion passing through the flues a' are impinged against the inclined wall. If desired, however, the flue may be run straight from the 90 furnace, as shown in Fig. 2. In such cases I prefer to support the center of the flue by means of pillar a⁴. This construction raises the flue A' above the ground-line and gives a larger space for the sand to accumulate. In 95 the device shown in Fig. 1 the sand falls on each side of the flue A'.

When in operation, the sand or gravel is shoveled into the top of the drier and works its way downward between the flues, which 100

are so arranged that a flue is placed immediately below the space between the flues above it. The space between the walls gradually becomes less, so that the sand or gravel 5 as it becomes dry reaches the hottest point. As the moisture causes the clogging of the sand or gravel, its removal causes the material to become granular, and by the time it reaches the flue A' it has been thoroughly 10 dried and escapes through the spaces a^5 between the flue A' and the side walls. The arrangement of the flues creates cross-currents in the flowing matter, so that the rubbing of the clogs or clods against each other 15 wears away the dried part of the matter from that which is held together by the moisture unexpelled.

What I claim as new is—

1. In a sand-drier, the combination of a furnace, a drying-chamber having inclined side walls, a vertical flue or chamber A² at the rear end of the drying-chamber, a flue connecting the furnace and said vertical flue and located between the lower ends of the side walls, a 20 vertical flue or chamber A³ at the rear of the furnace, and flues connecting the front and vertical flues or chambers and arranged in substantially a wedge-shaped form between the inclined side walls.
2. In a sand-drier, the combination of a furnace, a drying-chamber having inclined side 25

walls, a vertical flue or chamber A² at the rear end of the drying-chamber, a flue connecting the furnace and said vertical flue or chamber and located between the lower ends of the side 30 walls, a vertical flue or chamber A³ at the rear end of the furnace immediately over the connecting flue, and flues connecting the front and vertical flues or chambers and arranged in substantially a wedge-shaped form between 40 the inclined side walls.

3. In a sand-drier, the combination of a furnace, a drying-chamber having inclined side walls, a vertical flue or chamber A² at the rear end of the drying-chamber, a flue having an inclined part in the rear of the furnace connecting the latter with the said vertical flue and located between the lower ends of the side walls, a vertical flue A³ at the rear end of the furnace and having an inclined bottom which serves as the top of the inclined part of the main flue, and flues connecting the front and rear flues and arranged in substantially a wedge-shaped form between the inclined side walls.

In testimony whereof I affix my signature in presence of two witnesses.

EDWARD H. CALLAWAY.
